R. B. FINN

APPARATUS FOR THE PRODUCTION OF METALLIC DUST

Filed June 12, 1926

UNITED STATES PATENT OFFICE.

ROBERT B. FINN, OF SAN FRANCISCO, CALIFORNIA, ASSIGNOR TO JOHN FINN METAL WORKS, OF SAN FRANCISCO, CALIFORNIA.

APPARATUS FOR THE PRODUCTION OF METALLIC DUST.

Application filed June 12, 1926. Serial No. 115,635.

This invention relates to a process and apparatus for the production of metallic dust and has particular reference to the production of zinc dust.

5 The principal object of this invention is to produce an apparatus wherein zinc dust will be formed in a pure state, free from any oxides or other impurities.

Another object is to produce an apparatus 10 which is simple in construction, cheap to manufacture and one which will accomplish the objects set forth.

Other objects and advantages will be apparent during the course of the following 15 description.

In the accompanying drawings forming a part of this specification, and in which like numerals are employed to designate like parts throughout the same,

20 Figure I is a vertical cross-section of a heating chamber with a retort positioned therein and a condensing chamber attached to the neck of the retort, my invention being positioned in the bottom of the condensing chamber,

Figure II is a fragmentary detail top plan view of my scraper in its initial scraping position,

30 Figure III is a fragmentary detail top plan view of my scraper in its second position,

Figure IV is an enlarged fragmentary detail view showing the scraper in said elevation and in scraping position.

35 In the production of zinc dust, the metal to be vaporized is placed within a retort, the retort being positioned within a heating chamber and in such a position that the neck of the retort projects to a point outside of 40 the heating chamber. I then position a condensing chamber adjacent the heating chamber in such a manner that the neck of the retort extends into the condensing chamber and in order to prevent the admixture of air

45 with the products emanating from the neck of the retort, I lute any openings which may exist between the retort and the condensing chamber. The lower portion of the condensing chamber consists of a pan into which the 50 products of the condensing chamber are adapted to drop.

It is within this pan that I position my

invention which consists primarily of means for collecting the oxides which form in the condenser during the first period of operation, which oxides must be collected and protected in such a manner that they will not contaminate the products to be later formed within the condensing chamber.

The construction of the heating chamber 60 retort and the condensing chamber is old in the art and will only be briefly referred to. By now examining the drawings, it will be noted that the numeral 5 designates a furnace having a heating chamber 6, within 65 which a retort 7 is positioned; the firebox is indicated in dotted lines at 8.

The neck 9 of the retort extends to a point outside of the wall 5 of the furnace and is adapted to project through the wall 70 of the condenser, the upper section of which is designated by the numeral 11.

An angle iron shelf 12 is secured to the side of the condenser and serves to support the luting 13 which forms a seal between the 75 neck of the retort and the wall of the condenser. At 14 I have shown a pan which is provided with an annular channel 16 into which the upper portion of the condensing chamber rests.

80 This connection between the pan and the upper portion of the chamber is also luted as indicated at 17. Within the pan 14 I position a scraping element which consists of a scraper 18 and a cover 19. The cover 19 has 85 attached to each end thereof an outwardly projecting skid 21 and to the edges thereof are attached rollers 22 and 23 which are adapted to contact the sides of the pan.

At 24 I have shown an asbestos strip which 90 is attached to the cover and adapted to contact the sides of the pan so as to act as a seal between the sides of the pan and the cover. The cover also has attached thereto an angle iron member 26 to which a cable 27 is se- 95 cured.

The cable has a fitting 28 secured thereto into which is threaded a pull rod 29 having a handle 31.

The operation of my device is as follows:—

When the apparatus is assembled as shown in Figure I and heat is applied to the firebox 8, the temperature in the heating cham-

ber gradually rises, heating the retort 7. The material within the retort will in due time commence to distill over into the condensing chamber 11.

5 When the apparatus is first assembled the scraping element is placed in the pan in the position shown in full lines in Figure I, and it is of course obvious that as air is confined in the condensing chamber the result will be 10 that the first products coming from the retorts will contact this air in the condensing chamber resulting in a formation of oxide, and for the matter of discussion, we will call 15 this same zinc oxide, assuming that zinc is contained in the retort.

It is now a simple matter to observe the temperature of the retort which temperature will indicate to the observer exactly when the distilling process necessary commences, 20 and from experience the operator knows just how long it takes for the air in the condenser to become exhausted, which, of course, eliminates further production of the oxide.

As soon as this point has been reached 25 the operator grasps the handle 31 of the pull rod 29 and withdraws the same with the result that the withdrawal action pulling upon the cable 27 causes the scraping element to be drawn thereover from the position shown in full lines in Figure I to the dotted line position. This drawing over is indicated by the dot and dash line of this figure.

Further withdrawal of the rod causes the 35 scraper 18 to move across the bottom of the pan 14 and to scrape any oxide which may rest thereon into a pile beneath the cover 19. The skids 21 limit the amount of space the scraping element may be drawn 40 over in its initial movement, while the rollers 22 and 23 contacting the sides of the pan preventing the scraping element from becoming jammed. At the same time, the 45 asbestos strips at the sides of the cover contacting the sides of the pan prevent any of the oxides escaping or any of the zinc dust entering the chamber formed beneath the cover when the same is in contact with the end of the pan as indicated at A in Figure I.

50 After the rod has been withdrawn from the pan the same is unscrewed from the fitting 28 and the opening through which the rod was withdrawn is luted so as to prevent further introduction of air into the chamber.

55 It will thus be seen that by the mere manipulation of a rod it is possible to effectively gather and protect the oxides initially formed in the condenser pan from mixing with the zinc dust to be later formed.

60 It is to be understood that the form of my invention herewith shown and described is to be taken as a preferred example of the same, and that various changes in the shape, size and arrangement of parts may be resorted to without departing from the spirit

of the invention or the scope of the subjoined claims.

Having thus described my invention, I claim:

1. In an apparatus of the character described, a condensing pan, a scraping element having a cover portion formed integral therewith, said scraping element adapted to initially rest upon the pan in a horizontal position and means for upsetting said scraping element so that the same will assume a vertical position, said means serving to move said scraping element over the bottom of said pan, for the purpose specified. 70

2. In an apparatus of the character described, the combination with a condensing pan, a scraping element positioned within said pan, said scraping element being angular in shape, skids secured to said scraping element, said scraping element initially lying in a horizontal position, means for raising said scraping element to a vertical position, said means serving to move said scraping element over said pan, for the purpose 80 specified. 90

3. In an apparatus of the character described, the combination with a condensing pan, a scraping element comprising an angularly shaped member, a portion of said member serving as a cover, a portion of said scraping element serving as a scraper, skids formed on said scraping element, the scraping portion of said element initially resting in a horizontal position, a cable secured to said element, a bar secured to said cable and adapted to be withdrawn from said pan for the purpose of raising said scraping element to a vertical position and so as to cause said cover to assume a horizontal position, for 95 the purpose specified. 100

4. In an apparatus of the character described the combination with a condensing pan, a scraping element comprising an angularly shaped member, a portion of said member serving as a cover, a portion of said scraping element serving as a scraper, skids formed on said scraping element, the scraping portion of said element initially resting in a horizontal position, a cable secured to said element, a bar secured to said cable and adapted to be withdrawn from said pan for the purpose of raising said scraping element to a vertical position and so as to cause said cover to assume a horizontal position, and rollers secured to said cover and adapted 110 to contact the sides of said pan. 115

5. In an apparatus of the character described the combination with a condensing pan, a scraping element comprising an angularly shaped member, a portion of said member serving as a cover, a portion of said scraping element serving as a scraper, skids formed on said scraping element, the scraping portion of said element initially resting 125 in a horizontal position, a cable secured to 130

said element, a bar secured to said cable and adapted to be withdrawn from said pan for the purpose of raising said scraping element to a vertical position and so as to cause said cover to assume a horizontal position, rollers secured to said cover and adapted to contact the sides of said pan, and non-inflammable fabric strips secured to the edges of said cover portion and contacting the sides of said pan, for the purpose specified. 10
5 In testimony whereof I affix my signature.

ROBERT B. FINN.
